UNITED STATES PATENT OFFICE.

ALBERT C. OPPENHEIMER, OF CINCINNATI, OHIO.

MACHINE FOR MAKING INSOLES.

1,079,019.

Specification of Letters Patent.

Patented Nov. 18, 1913.

Application filed May 28, 1913. Serial No. 770,417.

To all whom it may concern:

Be it known that I, ALBERT C. OPPENHEIMER, a citizen of the United States, residing at Cincinnati, in the county of Hamilton and State of Ohio, have invented new and useful Improvements in Machines for Making Insoles, of which the following is a specification.

The object of this invention is to provide a lip-turning machine embodying certain improvements and refinements, whereby a simplified structure results and the desired sequence of operations is performed in a felicitous manner.

15 A further object is to provide an improved and novel lip-turning machine capable of making a double lip.

Additional objects, going to make up the ultimate perfection of the entire machine, 20 will appear as the specification proceeds and the nature of the invention more fully appears.

With these objects in view, the invention resides in the novel construction, combination and arrangement of parts, as will be hereinafter fully described in the specification, summed up in the claims, and illustrated in the drawings.

In the accompanying drawings, I have 30 illustrated the preferred embodiment of my invention capable of carrying out the underlying principles thereof; and in these drawings, in which like reference-characters denote corresponding parts throughout the 35 several views: Figure I is a top plan view of my machine; Fig. II is a longitudinal, vertical sectional view through my machine; Fig. III is an end elevation of the machine; Figs. IV and V are fragmentary 40 detail views, illustrating the different sequential positions of certain parts of my machine at successive stages in the operation of the latter.

Referring, now, in detail to the drawings: 45 1 indicates the supporting-frame of my machine, sustaining the working parts of the apparatus. The particular configuration of the frame is immaterial, as the latter forms no part of my invention.

50 2 indicates a drive shaft supported in bearings in the frame 1 and carrying, toward one end thereof, a pulley 8 loose thereon and a pulley 9 fast thereon, by which the shaft may be driven from any suitable 55 source of power. The drive-shaft 2 also carries, fast thereon, a pulley 10 and a pulley

10^a, the former of which, through a connecting belt 10^b passing over a pulley 11 fast on a shaft 3 suitably supported in bearings in the frame 1, drives said shaft 3; and 60 the latter of which, through a connecting belt 10^c passing over a pulley 6^a fast on a shaft 6 suitably supported in bearings in the frame 1, drives said shaft 6. The shaft 3 carries, fast thereon, a worm-pulley 12 65 meshing with a gear-wheel 13 fast on a vertical shaft 4 suitably supported in bearings in the frame 1. The shaft 4 carries, at the top thereof, a lip-roll 16 having an annular lip or flange 16^a at the top thereof, adapted 70 to overlie a work-table 17 carried at the top of a revoluble and vertically-reciprocable shaft 5 suitably supported in bearings in the frame 1. The shaft 4 also carries, fast 75 thereon, a pinion 15 meshing with a gear 19 fast on the shaft 5.

Carried by the lower end of the shaft 5 is a saddle 39 for connection with a foot-treadle (not shown), whereby the shaft 5 may be lowered. The shaft is returned to 80 normal position, after downward movement thereof, by a spring 20 seated in a socket 20^a in the frame 1, and bearing against the lower end of the work-table spindle 17^a.

Fast on the shaft 6 is an eccentric 21, 85 working in an eccentric-saddle 22 operatively connected to an eccentric-plunger 26, preferably through the medium of a screw 24^a in two sections, which are reversely threaded and united by a turn-buckle 90 24. The eccentric-plunger 26 terminates in a yoke 26^a, between which is pivoted, on a pin 36, a head 26^b carried by the screw 24^a. The eccentric plunger 26 reciprocates in bearings in the upper portion of the frame 1, and is covered for a portion of its length by a removable plate 34 suitably secured to 95 the top of the frame 1.

Suitably carried by the end of the eccentric plunger 26 is a turret 27. Advantageously, the turret is adjustably carried by said plunger, so as to be capable of adjustment to different angles of inclination with respect thereto, and, to this end, I prefer to provide the turret 27 with an arm 27^a, 100 which may be clamped to the plunger 26 by a set-screw 27^b. A collar 29^a, seated in a socket 27^{ab} in the turret, encircles the tool-spindle 29^b and is secured thereto, and a coiled spring 36 is interposed between said 105 collar and a plug 30 seated in the upper end of said socket 27^a, whereby the tool-spindle 110

29^b reciprocable in said screw-plug 30 is returned to normal position after upward movement thereof. The plug 30 is threaded into an interiorly-threaded collar 31 integrally carried at the top of the turret 27. A nut 30^a is screwed on the threaded top of the tool-spindle 29^b. The forming-in tool 29 is, at its lower end, formed with a beveled or inclined surface 29^c, as shown, which serves to raise the lip upward. The forming-in tool thus constitutes, as it were, a plow.

Rigidly carried by the frame 1 is an arm 32, which is, preferably, rectilinearly adjustable by a set-screw 32^a. The arm 32 carries, at one end thereof, a spindle 32^b. Desirably, this spindle is vertically adjustable, by a set-screw. The spindle carries, at its lower end, a tool 33 formed with an inclined or beveled surface, constituting a plow.

20 Operation: The channel is cut in the insole before the latter is operated upon by my machine, which is used simply to turn the two lips up from a light-weight insole, thereby composing one unit of a solid lip, that 25 would be obtained by using a better quality of stock, whereby the cost of production of insoles is reduced. In the operation of turning up the lips of an insole, the work-table 17 is lowered to admit the insole between 30 the work-table and the lip-roll 16^a. The forming-in tool 29, having the flexibly or 35 yieldingly-supported spindle 29^b, will adjust itself to any thickness or irregularities of the insole. The work-table 17, and the lip-roll 16^a revolve to feed the stock. The stationary plow 33 starts the raising of the outside lip, the lip-roll 16^a coöperating therewith to turn the said outside lip upward. The tool 29 vibrates and acts to turn 40 up the inside lip, bringing both lips together with pressure; the tool 29 vibrating against the revolving lip-roll 16^a, which thus coöperates in the operation of turning up both lips and pressing them together.

45 Having thus fully described my invention, what I claim as new and desire to secure by Letters Patent of the United States is:

1. In a machine for turning up two lips 50 previously cut in an insole, a revoluble work-table, a stationary lip-turning tool, an incliningly-supported, vibrating tool provided with a beveled lip-turning surface, means

for vertically-yieldingly supporting said vibrating tool, means for varying the inclination of said vibrating tool, and a revoluble roll having its edge extending over the work-table, said roll feeding the stock and coöperating with said vibrating tool in turning up the two lips and pressing them together. 60

2. In a machine for turning up two lips previously cut in an insole, a revoluble work-table, a stationary lip-turning tool, a turret, a vibrating tool vertically-reciprocatingly carried by said turret, a plug seated in the upper end of said turret, a collar carried by said vibrating tool, a spring interposed between said plug and said collar, and a revoluble roll having its edge extending over the work-table, said roll feeding the stock 70 and coöperating with said vibrating tool in turning up the two lips and pressing them together.

3. In a machine for turning up two lips previously cut in an insole, a revolving work-table, a stationary lip-turning tool, a vibrating tool provided with a beveled lip-turning surface, means for vertically-yieldingly supporting said vibrating tool, and a revoluble roll having its edge 80 extending over the work-table, said roll feeding the stock and coöperating with said vibrating tool in turning up the two lips and pressing them together.

4. In a machine for turning up two lips previously cut in an insole, a revolving work-table, a stationary lip-turning tool, a vibrating tool provided with a beveled lip-turning surface, said vibrating tool being supported in an inclined position, 90 a reciprocating plunger, a turret carrying said vibrating tool and adjustably clamped to said plunger so as to be held in any desired position of inclination with respect to said work-table, and a revoluble feed-roll having its edge extending over the work-table, and coöperating with said vibrating tool in turning up the two lips and pressing them together. 95

In testimony whereof, I have hereunto set my hand in presence of two subscribing witnesses.

ALBERT C. OPPENHEIMER.
